UNITED STATES PATENT OFFICE.

HORACE H. ALLEN, OF SAN FRANCISCO, CALIFORNIA, AND EUGENE P. GOLDEN, OF MERIDEN, CONNECTICUT, ASSIGNORS TO INTERNATIONAL SILVER CO., OF MERIDEN, CONNECTICUT, A CORPORATION OF NEW JERSEY.

GLASS-BOTTOM MUG.

No. 801,564

Specification of Letters Patent.

Patented Oct. 10, 1905.

Application filed April 27, 1905. Serial No. 257,792.

To all whom it may concern:

Be it known that we, HORACE H. ALLEN, residing at San Francisco, in the county of San Francisco and State of California, and EUGENE P. GOLDEN, residing at Meriden, in the county of New Haven and State of Connecticut, citizens of the United States, have invented a new and useful Improvement in Glass-Bottom Mugs; and we do hereby declare the following, when taken in connection with the accompanying drawings and the numerals of reference marked thereon, to be a full, clear, and exact description of the same, and which said drawings constitute part of this specification, and represent, in—

Figure 1, a side view, partially in section, of a glass-bottom mug constructed in accordance with our invention; Fig. 2, an under side view of the mug with the base and bottom removed.

This invention relates to an improvement in glass-bottom mugs, and particularly such as are formed from metal. In the use of such mugs the glass bottoms become broken and so that unless provision is made for removing the bottoms the mugs are discontinued. Various devices have been arranged to permit the removal of the bottom; but thus far such devices have a tendency to leak.

The object of this invention is to construct a mug with a removable bottom and make the same water-tight; and the invention consists in the construction hereinafter described and particularly recited in the claim.

The main body 2 of the mug may be of any ordinary design. These are usually formed from pewter or britannia-ware and are open at the bottom. If formed from soft metal, a ring 3, of hard metal, is located at the bottom of the body, and the face of this ring is formed with threads 4. The upper edge of this ring is formed with an inwardly-extending lip 6 formed in its under face with an annular rib 5. Between the upper face of the glass bottom 7 and the under face of the lip 6 a washer 8, of cork or other suitable material, is located. The base 9, also usually of soft metal, is formed with an inwardly-extending flange 10

and an upwardly-extending collar 11, corresponding in internal diameter to the external diameter of the lower end of the body 2. Secured to the flange 10 is a hard-metal bushing 12, forming a seat for the lower edge of the body and externally threaded for engagement with the ring 3 and extending up to the proper height, so that it will bear against the under face of the glass bottom 7 and force the same into close contact with the lip 4, causing the rib 5 to be forced into the washer 8. At the same time the collar 11 will overlap the lower end of the body. If the cup be made from hard metal, the ring 3 and bushing 12 may be formed integral with the body and base respectively. If the glass bottom becomes broken, it is only necessary to unscrew the base from the body and remove the bottom and substitute another one therefor. The base may then be again screwed into position, the washer packing a joint between the ring and the bottom so as to make a water-tight joint, the bushing and collar also coating with the lower edge of the mug for the same object. It will thus be seen that by a very simple arrangement of parts glass-bottom mugs may be produced the bottoms of which may be readily removed and replaced, and at the same time the possibility of leakage is practically avoided.

Having fully described our invention, what we claim as new, and desire to secure by Letters Patent, is—

1. A glass-bottom mug consisting of a body open at the bottom and having an internally-threaded ring at its lower edge, said ring formed with an inwardly-extending lip having a rib in its under face combined with a glass bottom adapted to set inside the ring, a washer located between the upper face of the bottom and the said lip, and a base adapted to be connected with said bottom and having a bushing engaging with said ring and holding the bottom in place, substantially as described.

2. A glass-bottom mug consisting of a body, a ring located at the lower edge thereof, a lip projecting inward from the upper edge of said

ring, an annular rib in the under face of said lip, a glass bottom adapted to set within said ring, a washer arranged between the upper face of said bottom and the said lip, a base 5 having an inwardly-extending flange, and an upwardly-extending collar, a bushing secured to said flange and adapted to engage with said ring and hold the bottom in place, said collar extending upward over the lower edge of said 10 body, substantially as described.

In testimony whereof we have signed this

specification in the presence of two subscribing witnesses.

HORACE H. ALLEN.
EUGENE P. GOLDEN.
